UNITED STATES PATENT OFFICE

FREDERIC A. DAVIDSON, OF BAYSIDE, NEW YORK, ASSIGNOR TO AMERICAN SAFETY DEVICE CO., OF NEW YORK, N. Y., A CORPORATION OF NEW YORK

APPARATUS FOR USE IN SETTING BUILDING STONE

Application filed June 10, 1930. Serial No. 460,129.

This invention relates to apparatus for use in setting building stone, and has for its general object and purpose to provide means whereby the workmen standing upon the platform of a suspended scaffold may with ease and facility, direct the stone to its proper position in the wall structure.

More particularly, the apparatus includes in combination with the suspended scaffold, a suspended horizontal rail for a traveling carriage which may be vertically adjusted as the construction of the building wall progresses, and the said carriage is provided with stone setting means operable from the scaffold platform.

It is also another object of the invention to provide a suspended scaffold with an improved supporting means for the overhead protection or covering which will afford adequate protection to the stone masons, without interfering with or obstructing the free manipulation of the stone positioning or setting means.

With the above and other objects in view, the invention consists in the improved apparatus for use in the setting of building stones and in the form, construction, and relative arrangement of its several parts as will be hereinafter more fully described, illustrated in the accompanying drawings, and subsequently incorporated in the subjoined claims.

In the drawings, wherein I have illustrated one simple and satisfactory embodiment of my present improvements, and in which similar reference characters designate corresponding parts throughout the several views,—

Figure 1 is an end elevation with certain parts shown in section illustrating one practical application of the preferred embodiment of my invention;

Fig. 2 is an enlarged detail elevation showing the manner of mounting the vertical standards or uprights of the overhead protection support at the outer side of the scaffold;

Fig. 3 is a detail horizontal section taken on the line 3—3 of Fig. 2;

Fig. 4 is an enlarged detail view similar

to Fig. 2, illustrating the means for mounting the uprights of the overhead protection support at the inner side of the scaffold;

Fig. 5 is a detail side elevation of certain of the parts shown in Fig. 4, and

Fig. 6 is a fragmentary plan view of the transverse angle bar connecting the opposite ends of the vertical uprights of the protection support.

Referring in detail to the drawings, in Fig. 1, I have shown a portion of a building in the course of erection, and in which the wall indicated at W is constructed of stone blocks. It is the general practice in setting these stone blocks to hoist the individual blocks from the ground by cables moving over sheaves on a swinging boom such as that indicated at B, suitably mounted upon the frame structure of the building. The operator controlling the swinging movements of this boom, therefore, is relied upon to properly operate the same in response to signals so as to position the suspended stone longitudinally of the wall structure at the proper point for setting, the stone being guided to its final position by the workmen on the scaffold. Such operations are comparatively time-consuming, and a large area of ground space is also occupied by the stone blocks which are unloaded from the trucks. These piled stones on the ground being practically unprotected, are liable to breakage or damage. It is the purpose of my present invention to obviate these disadvantages of the present method of stone setting in the erection of buildings and to also expedite the proper setting of the individual stones and therefore, the completion of the building operation.

To the above end, the suspended scaffold indicated generally at 5 which extends horizontally along the side of the building, is provided at its inner and outer edges at longitudinally spaced intervals with the usual hoisting devices shown at 6 upon the drums of which the suspending cables 7 attached at their upper ends in any suitable manner to the beam or outrigger 8 are wound in raising or lowering the scaffold.

For the protection of the masons or work-

men standing upon the scaffold platform against possible injury by falling materials, it is usual to provide an overhead protecting covering or decking as shown at 9. This 5 decking consists of a plurality of longitudinally extending planks or boards which are removably arranged upon supports mounted upon the frames of the hoisting devices 6. In the present instance, the support 10 associated with each pair of the hoisting devices, consists of the tubular metal uprights or standards 10 and 11 respectively. The standard 10 is of somewhat less length than the standard 11 and has its lower end engaged in a socket 13 formed upon the upper end of a bracket casting 12. The lower end of this casting is bifurcated as clearly shown at 14 in Fig. 5 of the drawings, the spaced arms thereof being of channel shaped cross 15 sectional form to receive the upper end of the inner vertical frame member 6' of the hoisting device 6 which is located next adjacent to the building wall W. Thus, while the inner edge of the scaffold platform is closely 20 adjacent to the face of the building wall, the supporting standard 10 will be spaced outwardly an appreciable distance therefrom. The upper ends of the spaced vertical frame bars of the hoisting device 6 are connected 25 in the usual manner by a transverse rod 15 upon which a cable guiding sheave is loosely mounted. The spaced lower end portions of the casting 12 are provided with angularly disposed flanges having openings at their 30 lower ends to receive a pin 16 extending beneath the end of the rod 15 to thereby retain the bracket member 12 in its applied position on the upper end of the frame bar 6'.

To the outer vertical frame bar 6^a of the 40 other hoisting device at the outer edge of the scaffold platform, vertically spaced angular bracket members 17 are suitably secured, one leg of each of these angular brackets being channeled as at 18 to prevent turning or pivoting movement of the bracket. The other arm of each bracket member has an opening formed therethrough to receive a cylindrical downwardly extending lug 20 formed on the angularly offset bracket member 21 which is 45 riveted or otherwise securely fixed to the supporting standard 11. Each of the lugs 20 at its end is provided with a transverse aperture therethrough to receive a locking key or pin 22 for retaining the lug in connection 50 with the bracket member 17.

At their upper ends, the standards 10 and 11 receive the heads 23 and 24 respectively, formed with flanges 23' and 24' which are riveted or bolted or otherwise secured to the 55 vertical web of a transverse angle bar 25. The heads 23 and 24 and the standards 10 and 11 are provided with registering openings to receive removable locking pins or keys 26 and 27 respectively. The horizontal 60 flange of the angle bar 25 at its opposite ends,

is formed with an upstanding lug 28 which prevents shifting movement of the overhead protection planking 9 longitudinally along the supporting angle bars.

It will be observed from reference to Fig. 1 of the drawings, that the angle bars 25 project a considerable distance beyond the uprights 10, and also beyond the vertical plane of the inner edge of the scaffold platform. In the laying of brick, the overhead 75 planking 9 will extend for the entire length of the angle bars 25 between the lugs 28 thereof, but in setting large heavy stone blocks, the innermost plank or board of the overhead protection decking 9 is removed so as to 80 permit the stone to be freely raised or lowered without obstruction and properly manipulated by the masons stationed on the platform to its required location in the building wall.

As shown in Fig. 1, by means of the hoisting cables operated from the boom B and attached to the cradle or sling 29, the heavy stone blocks may be quickly unloaded from the trucks and placed upon one or more of the 90 upper floors of the building above the point at which the stone is being set. Thus, the stone will be afforded a certain measure of protection against breakage or damage, and the ground surrounding the building is kept 95 clear of such construction materials.

In conjunction with the suspended platform for the masons or workmen, I provide a horizontally extending rail 30 adjustably suspended by means of the cables 31 to be 100 positioned at a suitable elevation above the overhead protection 9 of the scaffold, as the work progresses. Upon the base flanges of this rail, any desired number of carriages, one of which is indicated at 32, may be arranged for free horizontal traveling movement, each carriage having a block and tackle 33 suspended therefrom, the cable or rope 34 of which is provided at one of its ends with a suitable sling or grapple 35 105 whereby the individual stone blocks S may be removed from the floor of the building and swung outwardly into position for setting in the wall W. The other end of the cable or rope 34 extends downwardly closely adjacent to the inner edge of the overhead protection planking 9 to the scaffold of the platform 5 where it may be grasped and operated by the workmen standing upon the 110 platform. In this manner, it will be clear that since the carriage 32 may be easily and quickly moved along the rail 30 to a position above the precise point at which the stone is to be set, that the consumption of time incident to properly positioning and setting the stone in the wall structure will be reduced 115 to a minimum.

As shown in Fig. 6 of the drawings, I may secure to one side of each of the angle 120

bars 25, the spaced metal guide straps 36 for the scaffold hoisting cable 7.

From the foregoing description considered in connection with the accompanying drawings, the construction of my improved apparatus, its manner of operation, and several advantages in practical use will be fully and clearly understood. After the work has been completed, in dismantling the scaffold-
10 ing, the supporting standards 10 and 11 may be readily detached from the hoisting drum frames, and then swung inwardly towards each other upon the angle bar 25 so that the several parts of the supporting structure for
15 the overhead protection of the scaffold can be compactly arranged for convenience in transportation. I have herein shown and described an embodiment of my present improvements which has given very satisfac-
20 tory results in practical use. Nevertheless it is to be understood that the essential features thereof might also be incorporated in various other alternative structures, and I therefore, reserve the privilege of resorting
25 to all such legitimate changes therein as may be fairly embodied within the spirit and scope of the invention as claimed.

I claim:

1. In combination with a suspended scaffold and hoisting devices at the inner and outer edges of the scaffold platform each having a frame, supporting means for an overhead protection comprising inner and outer standards, means for detachably mounting
30 the standards at their lower ends upon the frame of the respective hoisting devices, and a transverse supporting beam for overhead protection planking connected to the upper ends of said standards, said beam projecting
35 inwardly beyond the standard mounted upon the frame of the inner hoisting device and beyond the inner edge of the scaffold platform, the overhead protection plank on the inner end of said transverse beam being
40 adapted to be removed to accommodate a stone hoisting and positioning device.

2. In combination with a suspended scaffold and hoisting devices at the inner and outer edges of the scaffold platform each having a frame, supporting means for an overhead protection comprising inner and outer standards, means for detachably mounting the standards at their lower ends upon the frames of the respective hoisting drums, a
50 transverse supporting beam for the overhead protection planking, and socket members secured to said beam at longitudinally spaced points to detachably receive the upper ends of said inner and outer standards.

60 3. In combination with a suspended scaffold and hoisting devices at the inner and outer edges of the scaffold platform each having a frame, supporting means for an overhead protection comprising inner and outer tubular standards, apertured parts fixed to
65

one side of the respective frames of the hoisting devices, said tubular standards having parts detachably engageable in said apertured parts, a transverse supporting beam for the overhead protection planking and spaced
70 socket members on said beam detachably receiving the upper ends of said tubular standards.

In testimony that I claim the foregoing as my invention, I have signed my name
75 hereto.

FREDERIC A. DAVIDSON.
